UNITED STATES PATENT OFFICE.

WILLIAM GADKE, OF PHILADELPHIA, PENNSYLVANIA.

CLEAT.

1,257,695.

Specification of Letters Patent. Patented Feb. 26, 1918.

Application filed January 22, 1916. Serial No. 73,684.

To all whom it may concern:

Be it known that I, WILLIAM GADKE, a citizen of the United States, residing in Philadelphia, Pennsylvania have invented a 5 Cleat, of which the following is a specification.

One object of my invention is to provide a relatively simple, inexpensive and substantial form of cleat whereby a rope may 10 be held from slipping, the construction and arrangement of parts of the cleat being such that said rope may be quickly and easily engaged with and disengaged from them.

These objects and other advantageous ends 15 I secure as hereinafter set forth, reference being had to the accompanying drawings, in which:

Figure 1 is a perspective view illustrating a cleat constructed according to my invention and showing a rope as held thereby;

Figs. 2 and 3 are respectively a plan and a side elevation of the cleat, and

Fig. 4 is a front elevation of the structure shown in Figs. 2 and 3.

In the above drawings 1 represents the 25 base plate of the cleat which may be held to a supporting structure in any desired manner as by screws, bolts or the like, there being shown screw holes 3 in said plate for the reception of screws 4. Formed integral with or otherwise rigidly attached to the base is a forked holding member having one of its branches 5 turned over in the form of an inverted U. The other branch 6 projects 30 approximately straight upward from the base in the plane of the hooked member 5 and like it, of rounded or substantially circular section, the space between the branch 6 and the main portion of the branch 5 being preferably substantially the same as the space between the two arms of said part 35 5, whose outer end is spaced away from the surface of the plate 1 in order to permit of the passage of a rope or cable.

Preferably formed integral with the structure 5-6 and projecting in a plane at right angles to the plane of the plate 1 as well as to that of said structure, is an auxiliary holding member 7 in the form of a finger or 40 arm extending outwardly and upwardly at an acute angle to said base. Said finger may be described as springing from the base 1 at a point adjacent the forked structure 5-6

to which it is preferably though not necessarily attached;—the edges of said finger 55 being rounded so as to give it a curved section, and its position being such that there is a narrow wedge-shaped space between it and the base as illustrated in Fig. 3.

When it is desired to hold a rope by means 60 of my cleat said rope, indicated at α in Fig. 1, is first passed between the base and the adjacent end of the hook and is thereafter carried through the space between said hook and the branch 6. From thence it is passed 65 under the finger 7 and is tightly drawn toward the apex of the wedge-shaped recess defined by this finger and the base, being finally led back under or adjacent the branch 6. As a consequence of this disposal of the 70 rope, a great part of the tension thereon is taken by the structure 5-6, and the remainder is taken by the finger 7 in such manner that it tends to more tightly wedge 75 or jam between it and the base 1.

Obviously the rope may be cast off of the cleat merely by moving its free end out from under the finger 7 after which it may be likewise freed from the branch 6 and hook 5 or if desired be allowed to render over 80 these members. Obviously the rope may be applied to the cleat in ways different from that above described, but in any case it is preferably so used that the members 5 and 6 serve to first receive it and thereafter it 85 is wedged under the finger 7 so that it is effectually held from slipping.

I claim:

1. A cleat including a base plate; a member in the form of a double reverse curve 90 mounted on said plate in a plane at right angles to the plane thereof; with a holding member extending in a plane substantially at right angles to the plane of the first member and making an acute angle with the base 95 plate.

2. A cleat including a base plate; a forked member thereon having the end of one of its branches turned over to form a hook and the other branch spaced away from the main part of said forked member; with a holding member extending in a plane substantially at right angles to the plane of the forked member and making an acute angle with the base plate.

3. The combination in a cleat of a base

plate; a branched member mounted thereon; and a holding member extending upwardly from said plate at an acute angle thereto from a point adjacent said first member and 5 in a plane at right angles to that of the branched member.

4. The combination in a cleat of a base

plate; two holding members in the same plane thereon of which one has an inverted U-shape; and a third member extending at 10 an acute angle to the base and in a plane substantially at right angles to that of said other holding members.

WILLIAM GADKE.
